UNITED STATES PATENT OFFICE.

OSCAR M. SHANNON, OF NEW YORK, N. Y.

FILE-CABINET.

1,146,739.

Specification of Letters Patent.

Patented July 13, 1915.

Application filed May 13, 1914. Serial No. 838,214.

To all whom it may concern:

Be it known that I, OSCAR M. SHANNON, a citizen of the United States, residing at the city of New York, in the borough of 5 Manhattan and State of New York, have invented certain new and useful Improvements in File-Cabinets, of which the following is a full, clear, and exact description.

This invention relates to improvements in 10 file cabinets.

The object of my invention is to construct a file section adapted for use for filing complete sets of architects', engineers' and builders' plans and the like in flat form in 15 which each set of plans will be easily accessible and the section as a whole will be compact, thereby adapting itself to use in offices and the like where the floor space is limited.

20 With this and other objects in view, my invention consists of the improved construction and combinations which will be hereinafter set forth in the specification and claims appended hereto.

25 In the drawings, Figure 1 is a plan of my improved cabinet with a portion of the top broken away showing one of the file sections extended; Fig. 2 is a sectional view on the line 2—2, of Fig. 1; and Fig. 3 is a 30 detail sectional view on the line 3—3 of Fig. 1.

Referring to the drawing, 1 designates a casing for the cabinet, preferably rectangular in form and of sufficient height, width 35 and depth to accommodate a sufficient number of file sections 2 for the purposes for which the cabinet is designed. The casing comprises a rear wall 3, side walls 4, and a top 5, the front and bottom being open. 40 The walls and top of the casing are of hollow metal construction filled with wood or any other light material which will add to their rigidity and strength without increasing their weight to any appreciable degree.

45 A series of partitions 6 arranged longitudinally within the casing divide it into compartments in which the file sections 2 are adapted to slide. Each section 2 comprises a frame, preferably rectangular in form, 50 having vertical front and rear walls 8 which are joined at their ends by the cross-pieces 9, all of which may be of wood, metal or any desired material. The section may be divided into two compartments by a thin, vertical partition 10 which runs substantially through the middle thereof and which

is held in place by grooves in the top and bottom boards of the frame into which the ends of the partition fit forming a mortise joint which will add materially to the rigidity of the partition. By dividing the section in this way, shallow compartments are provided which will not necessitate the storing of too great a number of sets of plans in one compartment and thus interfere with

60

their easy accessibility. This construction is preferable but not essential as these partitions instead of being in the middle of the sections may constitute the side walls thereof, thereby forming file sections having but one compartment. Arranged beneath each of the file sections are pairs of

70

rollers 11 at the front and rear ends thereof supporting the same from beneath which are preferably provided with rubber tires

75

to eliminate any noise which may be occasioned by the drawing out of a section of the cabinet over a floor. Fastened to the upper portion of the rear wall of each section are the angle-plates or brackets 12

80

which are secured in place by screws or the like. In Fig. 2 there are six of these angle-plates shown, but a greater or less number may be used depending upon the width of

85

the sections and the bulk of the sets of plans to be filed. These plates are arranged in pairs 13, 14 and 15, with the portions of

90

the plates normal to the rear wall facing each other. Alining holes are formed in each of the pairs of plates or brackets 95 through which pass the bolts 16 which are provided with nuts to securely hold them in place. Instead of the bolts, pins may be used, the ends of which are upset to securely retain them in position. These bolts or pins

95

act as pivots for the rectangular-shaped bars 17 which are bent at their ends around the bolts or are otherwise provided with an eye so as to swing freely thereon. The bars are arranged in their respective brackets 13, 14

100

and 15 so that they will occupy spaced parallel vertical planes to provide room for the several sets of plans to be filed. As shown, the two upper bars are spaced from each other but are arranged in close proximity to

105

the partition 10. The middle pair of plates carries one bar on each side of the partition which is arranged substantially in the middle of each compartment and is in spaced relation to the upper bars. There are two bars also carried by the lowest pair of plates on each side of the partition which are

110

spaced from each other and in a different vertical plane from the middle bar and are arranged near the open sides of the compartments.

- As shown, there are 10 bars for each section each of which is provided with slots 18 adapted to receive hooks carried by the clamps which are to be used to bind the sets of plans together, whereby the plans may be 10 hung in flat form in the section. Arranged on the front wall of each section are the supporting latches 19, corresponding to the sets of bars carried by the several pairs of angle-plates, which securely retain the bars 15 in place and support the ends of the same in horizontal planes, thus eliminating any strain on the bolts or pivot-pins due to the overloading of the bars. The hooked portions 20 of these latches are in spaced relation to correspond to the spaced relation of the bars so that they will retain the bars in 20 place in a line substantially parallel to the partition 10. Only three latches are shown on each side, for the double bars carried by 25 the upper and lower plates are both held by the same latch as one will rest against the other, as shown in Fig. 3. Arranged at the lower end of each of the sections are the doors or closures 21 pivotally mounted on 30 the rear walls of the same in close proximity to the outer edges. These doors extend from the bottom of the section to substantially the middle of the same and are adapted to retain the lower portions of the sets of 35 drawings or plans within the sections.

- A complete set of files or plans relating to one subject are clamped together at their upper edges by any desired form of fastening clip provided with a hook adapted to be 40 inserted in a slot 18 of the bars. The first set of plans are hooked to the upper bar which is in close proximity to the partition and the other sets of plans are then hooked to the other bars until the section is filled. 45 The door 21 is then closed to retain the lower portion of the plans within the section and so prevent them from being torn as the file sections are withdrawn or pushed back into the casing. Each of the partitions 6 is provided 50 at its front edge with a binding of felt or the like 22 which will engage with the beveled portion 23 of the front wall of the

section, thus preventing any dirt or dust from entering the cabinet when the sections are in their closed position and affording a 55 noiseless closing of the section.

Having thus described my invention, I claim:—

1. The combination with a file cabinet of a file section comprising a relatively shallow 60 compartment, a plurality of pivotally mounted bars arranged longitudinally in the upper portion of said compartment, said bars being arranged in spaced relation to each other and provided with slots for suspending 65 sheets of material in flat form, latches for the other end of said bars, said latches also being arranged in spaced relation, and a pivoted closure for the lower portion of said compartment for retaining the lower portion 70 of said sheets of material wholly within the file section.

2. The combination with a file cabinet of a file section, comprising a relatively shallow 75 compartment, a plurality of pivotally mounted bars extending across the upper portion of said compartment, said bars being arranged in spaced relation with each other and adapted to support sheets of material in flat form, latches for the other ends of said 80 bars, said latches being also arranged in spaced relation and a pivoted closure for the lower portion of said compartment for retaining the lower portion of the sheets of material wholly within the file section. 85

3. In combination with a file cabinet, a file section slidably mounted therein, said section comprising a vertically disposed shallow tray, a plurality of pivotally mounted bars extending across the upper end of 90 said tray and arranged in spaced relationship to each other, latches for the other end of said bars and a pivoted closure for the lower portion of said tray for retaining the lower portion of the sheets of material 95 adapted to be suspended from said bars wholly within the file section, whereby said section may slide freely in said cabinet.

In witness whereof, I subscribe my signature, in the presence of two witnesses.

OSCAR M. SHANNON.
